United States Patent Office.

ALBERT E. ROBERTS, OF DES MOINES, IOWA.

Design No. 4,605, dated January 24, 1871.

DESIGN FOR FRAMES OF SCHOOL-DESKS.

The Schedule referred to in these Letters Patent and making part of the same.

I, ALBERT E. ROBERTS, of Des Moines, in the county of Polk and State of Iowa, have invented certain Improvements in Designs for School-Desks, of which the following is a specification.

My invention is an improved design for the skeleton frames of my school-desk, originally patented August 17, 1869.

It consists—

First, in providing an enlarged bearing on the hinge upon which the desk and book-box revolve.

Second, in a locking-latch.

Third, in projections or rests for holding the book-box and desk firmly, when turned up for use or folded forward out of the way.

Fourth, in ornamental design, as hereinafter described.

The drawing represents my design by three figures.

Figure 1 is a perspective view of my locking-latch.

a is a pin, cast solid with it, by which the latch is lifted.

Figure 2 is a skeleton end of my book-box.

b is the enlarged bearing upon which it revolves.

c is a projecting pin, flat upon the left side, which catches on the locking-latch when my several pieces are combined as shown hereinafter.

d and *f* are projections or rests cast on the frame, and serve to hold the book-box and desk firm in its several positions.

Figure 3 is the skeleton end frame which supports my school-desk and seat, and shows the locking-latch, and also the end of the book-box in their combined positions, as designed to be used in a complete desk.

Parts of the end frame are cut away to show the locking-latch and the bearing *b*, and also the projections or rests *d* and *f*.

g is a projection cast on the skeleton end frame. When the desk is turned up for use the rest *d* presses on the under side of the projection *g*, and when the desk is folded forward and down, the rest *f* presses it on the upper side.

The latch is pivoted at the point *h*.

The pin on the latch, by which it is lifted, passes outwardly through the slot *m* in the frame.

When the desk is turned up for use the end of the latch catches the projection *c* and locks the desk firmly.

The basis of this locking device is in the ornamental form of the skeleton frame, which resembles the outline of an artist's palette.

The form shown and described is for the left end of a school-desk. It may be reversed to be used for the right side or end, if desired, and may be made of various sizes.

Claim.

I claim as my invention—

The skeleton end frame of a school-desk, composed of three pieces, formed, combined, and operated as illustrated in and by the accompanying drawing and specification.

ALBERT E. ROBERTS.
